C. W. HOWE ET AL

OIL PUMP

Filed June 21, 1923

UNITED STATES PATENT OFFICE.

CHARLES W. HOWE AND JESSE J. ROBERTSON, OF ARDMORE, OKLAHOMA.

OIL PUMP.

Application filed June 21, 1923. Serial No. 646,965.

To all whom it may concern:

Be it known that we, CHARLES W. HOWE and JESSE J. ROBERTSON, citizens of the United States, residing at Ardmore, in the 5 county of Carter and State of Oklahoma, have invented certain new and useful Improvements in Oil Pumps; and we do declare the following to be a full, clear, and exact description of the invention, such as 10 will enable others skilled in the art to which it appertains to make and use the same.

Our invention relates to improvements in oil pumps of the type employing a stationary working barrel having a standing 15 valve at its lower end, and a reciprocating plunger in said barrel provided with a traveling valve. Pumps of this character are provided with plunger packings for tight sliding contact with the working barrel 20 and with other packings at the lower end of the barrel which prevent leakage of oil around the mounting means for the standing valve. These packings become so worn that the pump parts must be entirely removed 25 from the well at frequent intervals in order that said packings may be adjusted or renewed. It is the object of our invention however to provide novel means whereby both packings may be effectively tightened, 30 simply by rotating the pump rod. We are aware that pumps have heretofore been provided which will permit of packing adjustments by rotating certain parts, but our invention aims to provide an improved construction which will be simple and inexpensive, yet highly efficient and reliable.

With the foregoing in view, the invention resides in the novel subject matter herein-after described and claimed, the description 40 being supplemented by the accompanying drawings.

Figure 1 is an elevation of a portion of the pump within a well casing, the working barrel being shown in vertical section.

Figure 2 is a vertical sectional view showing 45 the pump plunger engaged with the standing valve for effecting a packing adjustment, in the manner hereinafter described.

Figure 3 is a view similar to a portion of Fig. 1 but showing the plunger and the standing valve engaged with each other as indicated in Fig. 2.

Figure 4 is a horizontal section on line 4-4 of Fig. 3.

Figure 5 is a horizontal sectional view as indicated by line 5-5 of Fig. 2.

In the drawings above briefly described, the numeral 1 designates the working barrel of the pump which may be mounted in the usual well casing 2 in any desired 60 manner. A cup-shaped coupling 3 is threaded at 4 upon the lower end of the working barrel 1 and is provided with a bottom 5 having a flat sided central opening 6. This opening receives the flat-sided 65 lower end 7 of a short vertical tube 8 which rises from the bottom 5 into the barrel 1 and carries the usual cage 9 for a standing valve 10, said cage being formed with the common circumferentially spaced vertical 70 side bars 10. Adjacent its lower end, the tube 8 is provided with an outstanding flange 11 which rests upon the bottom 5 of the coupling 3, for the purpose of clamping a plurality of packing rings 12 against 75 the lower end of the barrel 1, preventing leakage at the lower end of the barrel. It will be seen that since the tube 8 is non-rotatable with respect to the coupling 3, that rotation of said tube in the proper direction, 80 will cause the coupling to thread upwardly upon the barrel 1, thus compressing the packing rings 12 to prevent further leakage, if it is discovered that some leakage has been taking place. We provide novel means 85 for so rotating the tube 8, as described below.

The pump plunger includes an upper tube 13 carrying a traveling valve 14 whose cage is adapted for connection with the usual 90 pump rod 15. Near its upper end, the tube 13 is provided with a downwardly facing shoulder 16 adapted to contact with the upper end of a compressible packing which surrounds said tube, this packing being by 95 preference formed of a suitable grade of rubber. The tube 13 extends below the packing 17 and is threaded in the upper end of a lower tube 18 and it will be seen that if this tube 18 is held against rotation 100 and the rod 15 is rotated to turn the upper tube 13, the latter will thread downwardly into the tube 18, thus compressing the packing 17 between the shoulder 16 and said tube 18 and causing radial expansion thereof, so 105 as to cause tight contact with the wall of the working barrel. For holding the tube 18 in this manner, we provide its lower end with a plurality of circumferentially spaced straight fingers 19 which are adapted for 110 reception between the vertical side bars 11 of the cage 9, when the rod 15 is lowered

sufficiently to permit this to take place. Then, it will be seen that turning of the rod 15 will effect the desired adjustment of the packing 17. Also, this rotation of the rod, 5 if the packing rings 12 are loose, will cause the coupling 3 to be threaded upwardly onto the lower end of the working barrel 1, thereby snugly tightening said packing rings to prevent leakage around them. Thus, it will 10 be seen that both the plunger packing and the packing at the lower end of the working barrel may be effectively tightened without the necessity of removing any parts of the pump from the well.

15 In order to prevent any returning of the tubes 13 and 18 to their initial positions, after they have been relatively adjusted, we prefer to provide some suitable means, such as the spring-pressed pin 20 carried by the 20 tube 18 and co-operable with a groove 21 in the tube 13, one side of the pin and one wall of the groove being appropriately beveled so as to permit relative turning of the tubes in one direction while preventing it in the 25 other direction.

As excellent results may be obtained from the details disclosed, these details are preferably followed. It is to be understood however that within the scope of the invention 30 as claimed, numerous minor changes may be made.

We claim:

1. An oil pump element comprising a cup-like coupling adapted to be threaded on the 35 lower end of a working barrel, and a standing valve carrying tube rising rigidly from and non-rotatable with respect to the bottom of said coupling, said coupling being adapted to contain packing rings to be

clamped thereby against the lower end of the 40 working barrel, rotation of said tube serving to thread said coupling tightly upon the working barrel to compress said packing rings.

2. An oil pump element comprising a cup-like coupling adapted to be threaded onto the lower end of a working barrel, said coupling having a flat-sided opening in its bottom, and a standing valve carrying tube rising from said bottom and having a flat-sided lower end received in said opening, whereby rotation of the tube will rotate the coupling, the lower end of said tube having an outstanding flange for clamping packing rings against the working barrel when said coupling is rotated and threaded further onto the barrel.

3. In a device of the class described, a working barrel, a cup-like coupling threaded on the lower end of said barrel, packing disposed between said barrel and coupling, a standing valve rising rigidly from and non-rotatable with respect to said coupling, an upper tube disposed in said barrel and provided with a shoulder, a lower tube threaded onto the lower end of said upper tube and provided with a shoulder, packing disposed between said shoulders, and coupling means carried by said lower tube and engageable with said standing valve for rotating the latter with said cup-like coupling to initially compress the first named packing and to successively compress the second named packing.

In testimony whereof we have hereunto affixed our signatures.

CHARLES W. HOWE.
JESSE J. ROBERTSON.
